UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METALLIC STRUCTURE FOR RAILWAY CARS.

Original application filed September 8, 1925, Serial No. 55,207, which is a division of application filed October 19, 1922, Serial No. 595,634. Divided and this application filed January 3, 1927. Serial No. 158,596.

My invention relates to the construction of railway cars and more particularly to metal end structures or walls for railway cars made of one or more metallic plates or panels formed with integral reinforcing, stiffening and bracing corrugations. However, this device may be incorporated in the construction of car side walls, floors, roofs or doors used in connection with railway cars of various types.

10 It is well known that the end walls of railway cars are more likely to be broken or otherwise injured than the side walls. This is due to the inertia thrusts and pressures caused by the shifting of the cargoes when the 15 train starts or stops. These thrusts may be local, tending to distort the end in some particular spot, as, for example, when a piece of piping or lumber shifts lengthwise imparting a blow against the end wall of the car; 20 or there may be a general tendency to break out the end wall as a whole or tear it away from the framing. For the purpose, therefore, of greater strength and durability, car ends have been constructed of metal plates 25 corrugated or formed with ribs to impart the desired strength, rigidity and resiliency.

One of the principal objects of my invention is to provide a corrugated or embossed metallic end structure for railway cars in 30 which the corrugations or embossments have a configuration and arrangement that impart to the structure a maximum capacity for resisting cargo thrusts, both local and general static or quiescent, and with sufficient resiliency to prevent permanent distortion due to 35 the thrusts of the loads, with a minimum weight of metal. It is important that structures of this sort should be as light as is possible, consistent with strength and durability, both for reasons of economy in manufacturing cost and also to keep the weight 40 of the car at a minimum.

A further object is to provide a corrugated metallic wall element that is practically possible to manufacture. A further object is to provide a metallic wall element with corrugations or embossments that resist to a greater degree torsional stresses, as well as brace the element, and the car end against diagonal 45 side thrusts or weaving.

In the drawings:

Fig. 1 is an end elevation of a box car equipped with my invention.

Fig. 18 is an enlarged section of a portion of the plate on line 9—9 of Fig. 5.

Like characters of reference designate like parts.

The end wall structure shown in the above 90 figures comprises a panel composed of a corrugated metal plate or plates.

Referring to Figs. 1 and 2. The corrugated plates 1, 2 and 3 extend across the car from side to side and are formed with integral 95 flanges 4 along the vertical edges which overlap and are secured to the frame members of the side walls 5 of the car by any suitable means.

The top edge of the end wall is secured 100

beneath the fascia boards 7 and the meeting edges of the plates overlap and are secured together by rows of rivets 8 and the lower edge of the end wall is secured to the end sill 9. Nailing strips 10 are secured to the plates 1, 2 and 3 by bolts and lining 11 is secured to the nailing strips 10.

Figs. 3 and 4 show the invention applied to a gondola type of car, wherein only one plate 12 is used to form the end panel which extends from side to side of the car and is provided along the vertical edges with flanges 13 which overlap and are secured to the frame members of the side walls 14 by any suitable means. The top edge of the plate is secured to the top chord 15 by rivets 16, while the lower edge is secured to rivets 17 to the end sill 18.

While the corrugations are shown pressed outwardly, and in horizontal arrangement, it is understood that the corrugations may be pressed inwardly, or partially inwardly and partially outwardly from the original plane of the plate or the corrugations may be placed in any position, for instance, vertically or diagonally. The plates or panels may be positioned vertically or horizontally and applied to any type of railway car.

Figs. 5 to 9 inclusive show the preferred form wherein the plate 30 is provided with a plurality of major corrugations 31 with preferably flat apices 36 which are spaced apart distances substantially equal to their respective widths and the parts 33 of the plate between the major corrugations are also preferably flat so that the configuration is symmetrical in cross section about a line midway between the outermost portions of these major corrugations, which line is the neutral axis of the section. Such a section is very strong on account of the amount of metal positioned away from the neutral axis and is also relatively rigid. These major corrugations 31 are preferably widest and deepest adjacent their middle portion and decrease in width toward their opposite ends, and the apices change from a flat to an arcuate configuration. The metallic plate is also provided with a plurality of aligned minor corrugations 32 which like between adjacent major corrugations 31 with their inner ends preferably terminating into the plate adjacent each other and with their outer ends terminating into the plate in line with the outer ends of the major corrugations.

The outer ends of the minor corrugations 31 have arcuate apices and the parts of the plate between these outer ends of the minor corrugations and the outer ends of the major corrugations are also arcuate so that they form a cross section of sinuous configuration, and, furthermore, the outer ends of the minor and major corrugations are of the same width and spaced apart substantially distances equal to their respective widths so that they

form a contiguous sinuous configuration symmetrical in cross section about a line midway between the outermost portions of the corrugations, which line is the neutral axis of the section. Such a section is very resilient and has a spring like action under load, and, furthermore, produces a very strong section for the amount of metal used. The minor and major corrugations merge into the plane of the plate by means of terminal portions 46 of any desired formation. By such an arrangement a corrugated metallic plate is provided which is relatively rigid adjacent the middle of the plate and relatively resilient adjacent the opposite end portions of the corrugations.

I have designed my invention for use in steel plates so that when the section modulus of any section (normal to the corrugations) is multiplied by a constant fibre stress the result equals the bending moment of that section for either a load concentrated at the middle of the corrugated part of the plate or for a load equally distributed over the corrugated part of the plate, thus showing that I have not sacrificed any required strength at the ends of the beams to obtain resiliency; in other words, by my construction I obtain a very strong plate which is also resilient.

As the major corrugations increase in width and depth toward their middle portion, the minor corrugations decrease in width and depth proportionately so that the lengths of the center lines of the metal of all cross sections of the corrugated portion of the plate are equal.

The major and minor corrugations may be positioned and dimensioned so that the length of the center lines of the metal of a cross section of the major corrugations adjacent their middle (see Fig. 7) is the same as the length of the center line of the metal of a cross section of the major and minor corrugations adjacent their end portions. (See Fig. 9). Furthermore, the corrugated plate may be so formed that the length of the center line of the metal of any cross section (for instance, as per Fig. 8) is equal to the length of the center line of the metal of any other cross section, that is, between the terminal portions. This is a material manufacturing advantage as it more evenly distributes the draw and stretch of the metal due to pressing the corrugations in the plate.

Figs. 16, 17 and 18 are detail enlargements of portions of the plate taken on lines 7, 8 and 9, respectively, of Fig. 5, showing the flat apex 36 of the major corrugations (Fig. 16) and the contiguous sinuous configuration of the major and minor corrugations 31—32 (Fig. 18).

Figs. 10, 11 and 12 are detail enlargements of a modified form of corrugation similar to Figs. 16, 17 and 18, respectively, wherein the apex of the major corrugation is arcuate,

while Figs. 13, 14 and 15 show both the major and minor corrugations having flat apices.

The major corrugations are preferably of uniform width for a short distance adjacent to their middle to provide greater strength for a greater portion of the plate and also to facilitate the changing of the forming dies when it is desired to increase or decrease the length of the corrugations or embossments.

10 Plates provided with a plurality of contiguous narrow corrugations possess a considerable amount of elasticity and when struck a blow deflect readily and regain their shape without distortion, whereas a plate provided with wide flat corrugations, though better able to carry quiescent loads, has not the resiliency of the former and is more readily distorted when struck a blow.

15 It is, therefore, desirable to design a plate that possesses great strength to withstand the sudden impact loads or blows with sufficient resiliency to resist distortion.

20 This application is confined to the construction wherein the minor corrugations are positioned between the major corrugations, while my application Serial No. 595,632, filed October 19, 1922 for corrugated metallic wall elements covers the construction wherein the middle portion of the major corrugation is 25 split into two or more minor corrugations.

25 This is a division of my co-pending application Serial No. 55,207, filed September 8, 1925, which is a division of application Serial No. 595,634, filed October 19, 1922.

30 The accompanying drawings illustrate the preferred form of the invention, though it is to be understood that the invention is not limited to the exact details of construction shown and described, as it is obvious that various modifications thereof within the 35 scope of the claims will occur to persons skilled in the art.

I claim:

40 1. A metallic plate having a plurality of major and minor corrugations terminating within the plate, said major corrugations decreasing in width and height from the middle toward the ends of the plate, said minor corrugations increasing in width from adjacent 45 the middle toward the ends of the plate, the cross sectional areas of said corrugated plate being substantially equal anywhere between the planes where said corrugations begin to terminate into the plane of the plate.

50 55 2. A metallic plate having a plurality of major and minor corrugations terminating within the plate, said major corrugations decreasing in width and depth from the center toward their ends, said minor corrugations positioned between said major corrugations merging from substantially the center and the plane of the plate, and increasing in depth and width until they merge with said major corrugations to form a contiguous configuration of uniform cross section.

3. A metallic plate provided with minor corrugations lying between wider corrugations, the length of the center line of the metal of any cross section of the corrugated plate being equal to the length of the center line of the metal of any other cross section. 70

4. A metallic plate provided with minor corrugations lying between wider and deeper corrugations, the length of the center line of the metal of any cross section of the corrugated plate being equal to the length of the center line of the metal of any other cross section. 75

5. A metallic plate provided with minor corrugations lying between deeper corrugations, the length of the center line of the metal of any cross section of the corrugated plate being equal to the length of the center line of the metal of any other cross section. 80

6. A metallic plate provided with a plurality of major corrugations spaced apart intermediate their ends distances equal to their width which decrease in width and in depth toward their ends, and a plurality of minor corrugations lying substantially between said major corrugations which increase in width and in depth toward the edges of the plate until said major and minor corrugations adjacent their ends are spaced apart distances equal to their width. 85 90

7. A metallic plate provided with a plurality of major corrugations having substantially flat apices which decrease in width and in depth toward their ends and a plurality of minor corrugations lying between said major corrugations which increase in width and in depth toward the edges of the plate, said major and minor corrugations being contiguous adjacent their ends and forming a sinuous configuration. 100 105 110

8. A metallic plate provided with a plurality of major corrugations having substantially flat apices spaced apart adjacent their centers distances equal to their width which decrease in width and in depth toward their ends and a plurality of minor corrugations lying between said major corrugations which increase in width and in depth toward the edges of the plate, until said major and minor corrugations are spaced apart distances equal to their width, said major and minor corrugations being contiguous adjacent their ends and forming a sinuous configuration. 115

9. A metallic plate provided with a plurality of major corrugations having substantially flat apices which decrease in depth toward their ends, and a plurality of minor corrugations lying between said major corrugations which increase in depth toward the edges of the plate, said major and minor corrugations being contiguous adjacent their ends and forming a sinuous configuration. 120 125

10. A metallic plate provided with a plurality of major corrugations which decrease in depth toward their ends, and a plurality of 130

minor corrugations lying between said major corrugations which increase in depth toward the edges of the plate.

11. A metallic plate provided with a plurality of major corrugations symmetrical in cross section about a line midway between the outermost portions of the corrugations which decrease in width and in depth toward their ends, and a plurality of minor corrugations 5 lying substantially between said major corrugations which increase in width and in depth toward the edges of the plate until they form a cross section symmetrical about a line midway between the outermost portions of 10 the corrugations.

12. A metallic plate provided with a plurality of major corrugations symmetrical in cross section about a line midway between the outermost portions of the corrugations which 20 decrease in depth toward their ends, and a plurality of minor corrugations lying substantially between said major corrugations which increase in depth toward the edges of the plate until they form a cross section symmetrical about a line midway between the outermost portions of the corrugations. 25

13. A metallic plate provided with a plurality of major corrugations of constant cross section for a short distance at the center of 30 the plate which decrease in width and in depth toward their ends, and a plurality of pairs of minor corrugations lying between said major corrugations which increase in width and in depth toward the edges of the plate. 35

14. A metallic plate provided with a plurality of major corrugations of constant cross section for a short distance at the center of the plate which decrease in depth toward 40 their ends, and a plurality of pairs of minor corrugations lying between said major corrugations which increase in depth toward the edges of the plate.

15. A metallic plate provided with a plurality of major corrugations which decrease in width and in depth toward their ends, and 45 a pair of aligned minor corrugations positioned substantially between adjacent major corrugations with their inner ends terminating into the plate and with their outer ends terminating into the plate in line with the outer ends of the major corrugations, said minor corrugations increasing in width and in depth toward their outer ends.

16. A metallic plate provided with a plurality of major corrugations which decrease in depth toward their ends, and a pair of aligned minor corrugations positioned substantially between adjacent major corrugations with their inner ends terminating into the plate and with their outer ends terminating into the plate in line with the outer ends of the major corrugations, said minor corrugations increasing in depth toward their 55 outer ends.

17. A wall for a railway car comprising a metallic plate secured to oppositely disposed frame members of the car, said plate provided with a plurality of major corrugations which decrease in width and in depth toward 70 their ends, said plate also provided with a plurality of minor corrugations lying substantially between said major corrugations which increase in width and in depth toward the edges of the plate until the major and minor corrugations terminate into the plate adjacent said oppositely disposed frame members. 75

18. A wall for a railway car comprising a metallic plate secured to oppositely disposed frame members of the car, said plate provided with a plurality of major corrugations spaced apart intermediate their ends distances substantially equal to their maximum width which decrease in width and in depth toward their ends, said plate also provided with a plurality of minor corrugations lying substantially between said major corrugations which increase in width and in depth 80 toward the edges of the plate until the major and minor corrugations are spaced apart distances substantially equal to their width adjacent said oppositely disposed frame members. 85

19. A wall for a railway car comprising a metallic plate secured to oppositely disposed frame members of the car, said plate provided with a plurality of major corrugations symmetrical in cross section about a line midway between the outermost portions of the corrugations which decrease in width and in depth toward their ends, said plate also provided with a plurality of minor corrugations lying substantially between said major corrugations which increase in width and in depth 90 toward the edges of the plate until the major and minor corrugations form a cross section symmetrical about a line midway between the outermost portions of the corrugations adjacent said oppositely disposed frame members. 95

20. A wall for a railway car comprising a metallic plate secured to oppositely disposed frame members of the car, said plate provided with a plurality of major corrugations which decrease in width and in depth toward their ends, said plate also provided with a plurality of minor corrugations lying substantially between said major corrugations which increase in width and in depth toward the edges of the plate adjacent said oppositely disposed frame members, the length of the center line of the metal of a cross section of the major corrugations adjacent the middle 100 of the plate being the same as the length of the center line of the metal of a cross section of the major and minor corrugations adjacent the edge of the plate. 105

21. A wall for a railway car comprising a metallic plate secured to oppositely disposed 110

frame members of the car, said plate provided with a plurality of truncated major corrugations which decrease in width and in depth toward their ends, said plate also provided with a plurality of minor corrugations lying substantially between said major corrugations which increase in width and in depth toward the edges of the plate until the major and minor corrugations are contiguous and 5 form a sinuous configuration adjacent said oppositely disposed frame members.

22. In a railway car structure, a metallic plate formed with a plurality of varying depth corrugations, some of said corrugations 15 extending between the opposite edges of the corrugated portion of the plate and other of said corrugations extending from said edges and merging into the plate adjacent the middle of said portion so as to provide a relatively rigid structure adjacent the middle of the corrugated portion of the plate and a relatively 20 resilient structure adjacent the edges of the corrugated portion of the plate.

23. In a railway car structure, a metallic 25 plate formed with a plurality of varying depth corrugations, some of said corrugations extending between the opposite edges of the corrugated portion of the plate and other of said corrugations extending from said edges 30 and merging into the plate adjacent the middle of said portion so as to provide a relatively rigid structure adjacent the middle of the corrugated portion of the plate which gradually becomes a relatively resilient 35 structure adjacent the edges of the corrugated portion of the plate.

24. In a railway car structure, a metallic plate formed with a plurality of corrugations, some of said corrugations extending between 40 the opposite edges of the corrugated portion of the plate and are relatively deep adjacent their middle portions and other of said corrugations extending from said edges and merging into the plate adjacent the middle of said 45 portion thus forming a greater number of relatively shallow corrugations adjacent their end portions so as to provide a relatively rigid structure adjacent the middle of the corrugated portion of the plate and a relatively 50 resilient structure adjacent the edges of the corrugated portion of the plate.

25. In a railway car structure, a metallic plate formed with a plurality of corrugations, some of said corrugations extending between 55 the opposite edges of the corrugated portion of the plate and are relatively deep adjacent their middle portions and other of said corrugations extending from said edges and merging into the plate adjacent the middle of said portion thus forming a greater number of relatively shallow corrugations adjacent their end portions so as to provide a relatively rigid structure adjacent the middle of the corrugated portion of the plate 60 which gradually becomes a relatively resilient 65

structure adjacent the edges of the corrugated portion of the plate.

26. In a railway car structure, a metallic plate formed with a plurality of corrugations, some of said corrugations extending 70 between the opposite edges of the corrugated portion of the plate and are relatively deep and relatively wider adjacent their middle portions and other of said corrugations extending from said edges and merging into the plate adjacent the middle of said portion thus forming a greater number of relatively shallow and relatively narrow corrugations adjacent their end portions so as to provide a relatively rigid structure adjacent the middle of the corrugated portion of the plate and a relatively resilient structure adjacent the edges of the corrugated portion of the plate. 75

27. In a railway car structure, a metallic plate formed with a plurality of corrugations, some of said corrugations extending between the opposite edges of the corrugated portion of the plate and are relatively deep and relatively wider adjacent their middle portions and other of said corrugations extending 80 from said edges and merging into the plate adjacent the middle of said portion thus forming a greater number of relatively shallow and relatively narrow corrugations adjacent their end portions so as to provide a relatively rigid structure adjacent the middle of the corrugated portion of the plate and a relatively resilient structure adjacent the edges of the corrugated portion of the plate. 85

28. A metallic plate provided with a plurality of major corrugations which decrease in width and in depth toward their ends, said plate also provided with a plurality of minor corrugations lying substantially between said major corrugations which increase in width and in depth toward their outer ends and terminate into the plate substantially in alignment with the major corrugations. 90

29. A metallic plate provided with a plurality of major corrugations spaced apart intermediate their ends distances substantially equal to their maximum width which decrease in width and in depth toward their ends, said plate also provided with a plurality of minor corrugations lying substantially between said major corrugations which increase in width and in depth toward the edges of the plate until the major and minor corrugations are spaced apart distances equal to 105 their width. 110

30. A metallic plate provided with a plurality of major corrugations symmetrical in cross section about a line midway between the outermost portions of the corrugations which decrease in width and in depth toward their ends, said plate also provided with a plurality of minor corrugations lying substantially between said major corrugations which increase in width and in depth toward 120 125 130

the edges of the plate until the major and minor corrugations form a cross section symmetrical about a line midway between the outermost portions of the corrugations.

- 5 31. A metallic plate provided with a plurality of major corrugations which decrease in width and in depth toward their ends, said plate also provided with a plurality of minor corrugations lying substantially between said 10 major corrugations which increase in width and in depth toward the edges of the plate, the length of the center line of the metal of a cross section of the major corrugations adjacent the middle of the plate being the same 15 as the length of the center line of the metal of a cross section of the major and minor corrugations.
32. A metallic plate provided with a plurality of truncated major corrugations which 20 decrease in width and in depth toward their ends, said plate also provided with a plurality of minor corrugations lying substantially between said major corrugations which increase in width and in depth toward the edges of the plate until the major and minor corrugations are contiguous and form a sinuous 25 configuration.

33. A metallic plate provided with a plurality of major embossments having flat 30 apices with the parts of the plate between the embossments also substantially flat, said major embossments decreasing in width and in depth toward their opposite ends, said plate also provided with a plurality of minor embossments lying substantially between the major embossments which increase in width 35 and in depth toward their outer ends and terminate into the plate substantially in alignment with the major embossments where the major and minor embossments have arcuate 40 apices and the parts of the plate between the ends of the major and minor embossments are also of arcuate configuration.

34. A metallic plate provided with a plurality of major embossments having flat 45 apices, said major embossments decreasing in depth toward their opposite ends, said plate also provided with a plurality of minor embossments lying substantially between the major embossments which terminate into the plate substantially in alignment with the major embossments where the major and minor embossments have arcuate apices and the parts of the plate between the ends of the major and minor embossments are also of 50 arcuate configuration.

35. A structure for a railway car comprising 55 a metallic plate secured to oppositely disposed frame members of the car, said plate provided with a plurality of major embossments having flat apices with the parts of the plate between the embossments also substantially flat, said major embossments decreasing in width and in depth toward their opposite ends, said plate also provided with a plurality 60

of minor embossments lying substantially between the major embossments which increase in width and in depth toward their outer ends and terminate into the plate adjacent said oppositely disposed frame members, where 70 the major and minor embossments have arcuate apices and the parts of the plate between the ends of the major and minor embossments are also of arcuate configuration.

36. A structure for a railway car comprising 75 a metallic plate secured to oppositely disposed frame members of the car, said plate provided with a plurality of major embossments having flat apices, said major embossments decreasing in depth toward their opposite ends, said plate also provided with a plurality of minor embossments lying substantially between the major embossments which terminate into the plate adjacent said 80 oppositely disposed frame members where the major and minor embossments have arcuate apices and the parts of the plate between the ends of the major and minor embossments are also of arcuate configuration.

37. A wall for a railway car comprising a 85 metallic plate secured to oppositely disposed frame members of the car, said plate provided with a plurality of truncated major corrugations which decrease in depth toward their ends, said plate also provided with a plurality 90 of minor corrugations lying substantially between said major corrugations which increase in depth toward the edges of the plate until the major and minor corrugations are contiguous and form a sinuous configuration adjacent said oppositely disposed frame members.

38. A metallic plate provided with a plurality of truncated major corrugations which decrease in depth toward their ends, said plate also provided with a plurality of minor corrugations lying substantially between said major corrugations which increase in depth 95 toward the edges of the plate until the major and minor corrugations are contiguous and form a sinuous configuration adjacent said oppositely disposed frame members.

39. A wall for a railway car comprising a metallic plate secured to oppositely disposed frame members of the car provided with a plurality of major corrugations which decrease in depth toward their ends and which terminate into the plate adjacent said frame members and a pair of aligned minor corrugations positioned between adjacent major corrugations with their inner ends terminating into the plate and with their outer ends terminating into the plate in line with the outer ends of the major corrugations.

40. A wall structure for a railway car comprising 125 a metallic plate secured to oppositely disposed frame members of the car provided with a plurality of varying width and varying depth major corrugations and a pair of aligned varying width and varying depth 130

minor corrugations positioned between adjacent major corrugations, having the upper minor corrugations longer than the lower minor corrugations, the outer ends of the 5 major and minor corrugations terminating within the plate substantially in alignment with each other adjacent said frame members, the maximum strength of the corrugated wall being substantially midway between the 10 frame members.

41. A metallic plate provided with a plurality of varying width and varying depth

major corrugations and a pair of aligned varying width and varying depth minor corrugations positioned between adjacent major corrugations, having the upper minor corrugations longer than the lower minor corrugations, the outer ends of the major and minor corrugations terminating within the plate substantially in alignment with each other, 15 the maximum strength of the corrugated wall being adjacent the middle of the major corrugations. 20

ARTHUR E. SMALL.
